CLAIM

The ornamental design for a headlight as shown and described.

DESCRIPTION

FIG. 1 is a front perspective view thereof;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a rear perspective view thereof.

As demonstrated by the figures of the present application, the claimed headlight includes a transparent lens. The transparent lens is illustrated as transparent to review the underlying design of the headlight, which forms part of the overall ornamental design. As one of ordinary skill in the art would understand, the lens is therefore not entirely visible in all regions in the figures where another part of the headlight is not positioned behind the lens.
